UNITED STATES PATENT OFFICE.

ROBERT H. LAIRD, OF TORONTO, CANADA, ASSIGNOR TO WILLIAM HENRY LAIRD, OF NEW YORK.

APPARATUS FOR VAPORIZING OIL.

SPECIFICATION forming part of Letters Patent No. 498,518, dated May 30, 1893.

Application filed September 28, 1892. Serial No. 447,196. (No model.)

To all whom it may concern:

Be it known that I, ROBERT H. LAIRD, gentleman, of the city of Toronto, in the county of York and Province of Ontario, Canada, have invented certain new and useful Improvements in Apparatus for Vaporizing Oil; and I hereby declare the following to be a full, clear, and exact description of the same.

In vaporizing crude oils it is found that in order to obtain the best results from the distillation the bulk must be distributed in thin sheets over a large generating surface, and that this distributed bulk must be heated, in the first instance, to a temperature of about 212° Farenheit, to generate what is commonly known as the alcoholic series of vapors and that after the alcoholic series of vapors have been obtained the residue must be subjected to heat ever and gradually increasing in temperature to obtain therefrom the oleic vapors of the different gravities; and the object of the invention is to construct a still by means of which the foregoing objects may be attained; and the invention consists essentially of a still of any suitable shape and size having arranged within its outer shell a series of distributing surfaces placed one above the other with an intervening space between them and adapted to hold a thin sheet of oil during the process of distillation, each of the distributing surfaces preferably consisting of a perforated metallic plate having a suitable sized circular opening through its middle through which passes a supporting standard or column adapted to hold the distributing surfaces firmly in place, pipes entering the still and adapted to convey heat from the generator to the still, a pipe for admitting oil from the mixing tanks to the still, a vapor dome located within the still and above the uppermost distributing surface, pipes for conducting the vapors from a vapor dome to the filters and means for drawing off the residue from the still; the whole device being constructed as hereinafter more fully set forth.

It the drawings:—Figure 1 is a perspective view of a still with the outer shell partially broken away showing the various distributing surfaces, the heating pipes, the vapor dome, pipes for conducting the vapors from the vapor dome to the filters and means for

introducing the oil into the still. Fig. 2 is a plan view showing the arrangement of the heating pipes located beneath each of these distributing surfaces exhibited in Fig. 1. Fig. 3 is an enlarged cross sectional view of an alternative form of still. Fig. 4 is a transverse sectional view on the lines *a—a* Fig. 3 showing the arrangement of the heating pipes located beneath each of those distributing surfaces shown in Fig. 3. Fig. 5 is a plan view of one of those distributing surfaces shown in Fig. 3.

Like numerals and letters of reference refer to like parts throughout the specification and drawings.

The still consists of an outer shell 1, constructed preferably of boiler plate. Located centrally within the outer shell 1 is a standard or upright column 2, on the outer face of which is formed a screw thread 3.

Located within the shell 1 is a series of perforated metallic plates 4 having a central opening 5 formed in them through which passes the standard or upright column 2 screw 75 threaded on its outer face. Surrounding the central opening 5 on the under side of the plate 4 is a collar 14° screw threaded on its inner face. As shown in Fig. 3 of the drawings these metallic plates 4 are six in number 80 but the number employed is predetermined and is regulated according to the size of the still. Each of the perforated metallic plates 4 is provided with a downwardly projecting flange 6 which rests upon a bracket 7. It 85 might here be stated that the upper surfaces of the metallic plates 4 are slightly inclined from the circular opening 5 downwardly to a point 4^a in close proximity to their peripheries 4^b from which point 4^a they are inclined 90 upwardly to the peripheries 4^b as shown in Figs. 1 and 3 of the drawings.

The downwardly projecting flange 6 is inclined from its upper edge inwardly toward the column or standard 2 to enable the upper 95 surface of the perforated metallic plate 4 next below it to overlap its lower edge 6^a. This construction permits the overflow of oil from the topmost metallic plate 4 to be fed to the upper surface of the metallic plate 4 next below it, repeating this operation to the lowermost metallic plate 4 within the still.

The supporting bracket 7 comprises a hub 7^a and arms 7^b radiating from said hub. The inner face of the hub 7^a is screw threaded to correspond with the screw threaded outer face of the standard or column 2. The column 2 passes through the hub 7^a and the engagement of the screw threaded inner face of the hub with the screw threaded outer face of the column or standard 2 permits of the bracket 10 being raised or lowered to any desired elevation along the said standard. Located on the under side of each of the metallic plates 4 is a series of perforated pipes 8 to each of which is supplied the heating fluid by means 15 of a supply pipe 9 leading from the generator which generator may be of any ordinary form.

The metallic plates 4 shown in Fig. 1 of the drawings it will be noticed are rectangular in shape and in them are two openings 5 through 20 each of which passes a standard or column 2; and that connected to each of the standards or columns 2 and on the under side of the metallic plate 4 is a bracket 7 comprising a hub 7^a and three outwardly radiating arms 7^b.

Again by reference to Fig. 3 of the drawings it will be noticed that I have modified the shape of the plates by making each of the said metallic plates 4 circular. Again by reference to the same figure it will be noticed that 25 formed centrally in them is an opening 5 through which passes a column or standard 2. It will also be noticed by reference to Fig. 4 of the drawings that the superheating pipes 3 located on the under side of the distributing plate 4 shown in Figs. 3 and 5 of the drawings are in the form of a spiral coil and that the innermost coil is carried outwardly beyond the outermost so that it may be connected to the return pipes 9^a.

By reference to Fig. 2 of the drawings it will be noticed that the heating pipes 8 shown therein are in the form of a rectangle having two T's or T branches 8^c one at either end of the distributing plate to each of which are 45 connected two side pipes 8^b and four intermediate pipes 8^d. Leading from the tank (which is not necessary to be shown in this application) and entering the upper portion of the still is a feed pipe 10 which is arranged 50 preferably over the middle of the still and is adapted to distribute the oil evenly in all directions. As the distributing plates shown in Fig. 1 are rectangular in shape I find it convenient to feed the oil from the feed pipe 55 10 to a perforated distributing pipe 10^a which would in turn feed the oil over a much larger area of the plate 4 than could be properly accomplished by the pipe 10. As shown in the same figure I have provided this still with 60 four feed pipes 10 which feed the distributing pipe 10^a.

The oil is introduced into the still by means of the feed pipe 10 which distributes it over the topmost perforated metallic plate 4 which 65 feeds its overflow to the metallic plate 4 next below it, which operation is repeated to the lowermost metallic plate 4. The heating fluid

is applied to the pipes A by means of the supply pipes 9 and passes through the perforations in the tops of said pipes 8 to the under 70 sides of the metallic plates 4. This steam acting on the oil converts the said oil into vapor which rises to the vapor dome A. The vapor dome A is located in the top of the still and above the uppermost of the perforated metallic plates 4.

When crude oil is being vaporized the heat first introduced to the still by means of the connection pipes 9 is at a temperature of about 212° Fahrenheit and generates from 80 the crude oil at this temperature what is commonly known as the alcoholic series of vapors. The alcoholic series of vapors as they are generated rise to the dome A and are conducted from the said dome to their respective filter by means of the pipe B. The pipe B is provided with a valve b which always remains closed except during the passage of the alcoholic series of vapors therethrough at which time it is opened. After the alcoholic 90 series of vapors have been obtained from the oil within the still the heat is increased in temperature to about 300° Fahrenheit at which temperature the lightest of the oleic vapors are given off and are conducted from the still by 95 means of the pipe C to their respective filter, the pipe C being always provided with a valve c which always remains closed except during the passage of the lightest of the oleic vapors therethrough. After the lightest of the oleic 100 vapors have been obtained the temperature of the heat is again increased to 450° Fahrenheit at which temperature the next lightest of the oleic vapors are given off and these oleic vapors rising from the dome A are conducted from the said dome to their respective filter by means of the pipe D provided with a valve d and after these oleic vapors 105 have been obtained the temperature of the heat is again increased to about 650° Fahrenheit at which temperature the last of the 110 third lightest vapors are given off and are conducted to their respective filter by means of a pipe F fitted with a valve e.

It might here be stated that the perforations in the pipes 8 on the under sides of the plates 4 are in the tops of the said plates so that when steam is used the condensation that will naturally occur during the continuance of the use of the steam will accumulate in the 115 bottoms of the said pipes and may be blown off from the pipes 3 into the return pipe 9^a by the pressure of the live steam.

Entering the bottom of the still 1 is an exhaust pipe 13 provided with a valve 13^a to 120 empty the still of its contents after the vaporizing is completed. The bottom 14 of the still is inclined to direct its contents toward the opening to the exhaust pipe 13.

Having thus fully described my invention, 130 what I claim as new, and desire to secure by Letters Patent, is—

1. In an apparatus for vaporizing oil the combination of an outer shell, a standard cen-

trally located within said outer shell, a series of perforated metallic distributing plates within said outer shell, a series of pipes located on the under side of each of the said distributing plates and entering the apparatus from the said outer shell, said pipes adapted to convey heat to the said distributing plates, brackets secured to the said standard and adapted to support the said distributing plates, a vapor dome located within said outer shell and above the said distributing plates, a supply pipe adapted to feed the oil to the said distributing plates and pipes adapted to carry off the vapors from the said vapor dome, substantially as described.

2. In an apparatus for vaporizing oil the combination of an outer shell, a series of metallic distributing plates within said outer shell, each of said distributing plates having its upper surface downwardly inclined from the middle to a point near the periphery and upwardly inclined from said point to its periphery, means for supplying oil to said apparatus, means for supplying heat to the said distributing plates and means for conducting

away the vapors as they are generated, substantially as described.

3. In an apparatus for vaporizing oil the combination of the outer shell, a series of metallic distributing plates suitably supported within said outer shell, the upper face of each of the distributing plates inclined downwardly from its middle to a point near its periphery and inclined upwardly from said point to its periphery, a downwardly projecting flange encompassing its edge, said flange inclined inwardly to enable the distributing plate next below it to overlap the lower edge of said flange, a supply pipe entering said outer shell and adapted to feed the oil to the distributing plates, a vapor dome within said outer shell and pipes entering said outer shell and adapted to carry away the vapors from the said vapor dome, substantially as described.

Toronto, July 6, 1892.

ROBERT H. LAIRD.
